UNITED STATES PATENT OFFICE.

BRONISLAW DOBAZENECKI, OF ROSLYN, NEW YORK.

METAL-SHEARING DEVICE.

Application filed September 25, 1920. Serial No. 412,846.

To all whom it may concern:

Be it known that I, BRONISLAW DOBAZENECKI, a citizen of Poland, residing in the city of Roslyn, county of Nassau, and State of New York, have invented certain new and useful Improvements in Metal-Shearing Devices, of which the following is a full, clear, and exact specification.

My invention relates to metal shearing devices and refers particularly to devices suitable for the shearing of various sizes of cuttings in metal sheets.

In the cutting of metal sheets it is frequently desirable to make openings of various sizes.

This is usually accomplished by having a number of machines each capable of cutting a particular size opening, which requires a considerable invested expense for machines and the necessity of considerable floor space; or by having a number of replaceable cutting members fixable within one machine, which requires the investment incident to such numerous cutting members and involves the danger of their loss or misplacement.

All of these difficulties are overcome by the device of my invention which allows of the cutting of various size openings without the use of loose and separable parts.

My device is further a means whereby both straight edges and openings may be cut with equal facility.

My device further presents a means whereby metal sheets may be punched by the simple insertion of the punching means into my device.

The simplicity, effectiveness and utility of my device are evident upon a consideration of the accompanying drawings, specification and claims.

In the accompanying drawings illustrating one form of my device similar parts are designated by similar numerals.

Figure 1 is a top plan view of one form of my device.

Figure 2 is an elevation of Figure 1 partly in section, a broken view of the upper member in a revolved position being indicated in dotted lines.

Figure 3 is a section through the line 3-3 of Figure 2.

Figure 4 is a section through the line 4-4 of Figure 2.

Figure 5 is a section through the line 5-5 of Figure 2.

Figure 6 is a section through the line 6-6 of Figure 2.

The particular form of my device shown in the accompanying drawings, comprises a base member 10 having the two extended spaced arms 11, 11. A transverse member 12 is slidable along openings 13, 13 of the arms 11, 11. The bearing 4 carries the revolute threaded bar 15, which is further supported by the bearing 16, and carries the bevel 17, which meshes with the bevel 18 carried by the revolute shaft 19, which in turn carries the bevel 20, meshing with the bevel 21 of the threaded revolute bar 22 supported by the bearings 23 and 24. The extremity of the bar 15 carries the handle 25 for ease of operation. The bar 15 meshes with the threaded hole 26 of one side of the member 12 and the bar 22 meshes with the threaded hole 27 of the other side of the member 12. The revolution of the handle 25 therefore will move the member 12 backwardly and forwardly. The arms 11, 11 carry two upwardly extended fixed knife edges 28, 28, and the slidable member 12 carries an upwardly extended fixed knife edge 29, the knife 29 being slidable within the knives 28, 28. Slidable within the upper member 30 is a box member 31, having downwardly extended knife edges 32, 32 and 33. A threaded revolute shaft 34, carried by the bearings 35, 36, meshes with the threaded hole 37 of the box 31, and carries a handle 38, the revolution of which slides the box 31 and the knives 32, 32 and 33 forwardly and backwardly.

The base 10 and the upper member 30 are pivotally connected at 39.

The other end portion of the base 10 carries the upwardly extended knife edge 40, and the corresponding end portion of the upper member 30 carries the downwardly extended knife edge 41.

The handles 42 and 43 serve as a means for the hand operation of the device.

Two similar foot-power movements are provided by the link systems comprising the link 44 pivotally attached to the upper member 30 at 45 and to the foot member 105 46 at 47, the latter being pivotally attached to the base support 48 at 49.

The operation of the device is as follows:

When it is desired to cut a straight line 110 the upper member 30 is placed in the position indicated by the dotted line of Figure

2, the metal inserted between the knives 40 and 41 and the knives brought together either by means of the handle 42 or the foot-power mechanism.

5 When it is desired to cut out a rectangular piece, the upper member 30 is placed in the position shown in Figure 2, the box 31 and the member 12 are placed in the desired position by means of the handles 38 and 10 25 and the upper member 30 brought downwardly by means of the handle 43 or the foot-power mechanism. A three sided cut is thus made in the metal, the fourth side of the rectangle may be cut by means of 15 the knife 29. It will thus be seen that rectangular pieces of varying lengths and at predetermined positions in the metal may be cut from the metal by sliding the members 12 and 31.

20 If it is desired to punch holes in metal sheets, the male punch 50 is screwed into a threaded hole in the box 31, and a block 51 is placed within the opening between the arms 11 11 of the base 10, the block 51 carrying a female member 52 corresponding to the male punch 50, the downward movement of the upper member 30 forcing the male punch into the female member. This device is indicated in dot and dash lines in 25 the drawings.

30 I do not limit myself to the particular size, number, shape or arrangement of parts as shown and described, all of which may be varied without going beyond the scope of my 35 invention as shown, described and claimed.

What I claim is:—

1. In a shearing device, in combination, 40 a base, two parallel spaced knives extending longitudinally on said base and carried thereby, a transverse member slidably mounted on said base between said parallel spaced knives, a knife carried by said transverse member, an upper member pivotally mounted on said base, a box member slidably 45 mounted in one end of said upper member, parallel spaced knives extending downwardly from said box member, a transverse knife associated with said parallel knives and extending downwardly from said box member, said box member and knives carried thereby adapted to cooperate with the knives carried by said base upon bringing said upper member into an operative relation with respect to said base.

50 2. In a shearing device, in combination, a base provided with spaced arms at one end thereof, upwardly extending knives carried by said arms, a transverse member slidably mounted between said arms, an upwardly extending knife carried by said transverse member, means for moving said transverse member longitudinally between said arms, an upper member pivotally mounted on 60 said base intermediate its ends, a box mem-

ber mounted in said upper member, parallel spaced cutting knives extending downwardly from said box member, a transverse cutting knife extending downwardly from said box member and arranged at one end thereof adapted to extend across the ends of said parallel knives, and means for swinging said upper member into an operative position whereby the knives on said base member cooperate with the knives on said box member carried by the upper member. 75

3. In a shearing device, in combination, a base provided with spaced arms at one end thereof, knives extending upwardly therefrom, a transverse member extending between said arms and knives carried thereby, said transverse member provided with means extending through longitudinally extending slots provided in said arms for guiding the same longitudinally, means associated with said last mentioned means for moving said transverse member longitudinally between said arms, a knife carried by said transverse member and extending upwardly therefrom, an upper member pivotally mounted on said base adjacent said arms, a box member slidably mounted in said upper member, parallel spaced knives extending downwardly from said box member, a transverse knife extending downwardly from said box member, and arranged adjacent the ends of said parallel knives, means for moving said box member longitudinally in said upper member, and means associated with said upper member for bringing said knives into a shearing position. 95

4. In a shearing device, in combination, a base provided with spaced arms at the forward end thereof, parallel spaced knives carried by said arms and extending upwardly therefrom, a transverse member slidably mounted between said parallel spaced arms, an upwardly extending knife carried by said transverse member, threaded means for moving said transverse member longitudinally between said arms, an upper member pivotally mounted adjacent its forward end on said base, a box member slidably mounted in the forward end of said member, cutting knives carried by said box member and extending downwardly therefrom, threaded means for moving said box member and cutting knives carried thereby longitudinally in the forward end of said upper member, and means associated with said upper member for bringing said cutting knives carried by said box member into a shearing position with said first mentioned cutting knives. 115

Signed at New York city in the county of New York and State of New York this 22nd day of September, 1920.

BRONISLAW DOBAZENECKI.
